UNITED STATES PATENT OFFICE.

CLARENCE W. TAYLOR, OF OAK PARK, ILLINOIS.

TRAIN-PIPE COUPLING.

No. 854,194.

Specification of Letters Patent.

Patented May 21, 1907.

Application filed January 7, 1907. Serial No. 351,056.

To all whom it may concern:

Be it known that I, CLARENCE W. TAYLOR, a citizen of the United States, residing at Oak Park, in the county of Cook and State of Illinois, have invented certain new and useful Improvements in Train-Pipe Couplings, of which the following is a specification.

My invention relates to improvements in automatic train pipe coupling, and the objects of my improvement are, first, to provide devices which will readily yield to the various positions and motions of the ends of the cars whether at rest or in motion; second, the provision of mechanism which automatically will open the passages connecting the fluid pipes when the couplings are made and close such passages when the connections are broken; and, third, the provision of means to prevent movement of the pipe coupling members relative to one another while in coupled position.

With the above and other objects in view, this invention consists of the novel features and the combinations and arrangement of parts hereinafter more specifically described; illustrated in the drawings, and particularly pointed out in the claims hereunto appended.

In describing the invention in detail reference is had to the accompanying drawings forming a part of this specification wherein like numerals of reference indicate corresponding parts throughout the several views, and in which

Figure 1 is a side elevation of two M. C. B. couplers with my automatic coupling apparatus attached to the underside thereof in coupled position. Fig. 2 is a side elevation of one M. C. B. coupler and my apparatus each in uncoupled position. Fig. 3 is a perspective of my improvement detached from the M. C. B. coupler. Fig. 4 is a vertical section on line 4—4 of Fig. 5. Fig. 5 is a front elevation of the pipe coupling member, and Fig. 6 is a front elevation of the hanger or ring portion of the depending bracket.

One embodiment of my invention will now be described.

On reference to Figs. 1 and 2 it will be seen that to the under side of an M. C. B. coupler 8, I attach what I call a depending bracket which consists of the part 9, and the hanger or ring portion 10, the latter preferably is made in two parts or halves, each half having an upper flange 11 and a lower flange 14. The part 9 is attached to the M. C. B. head

8 in the common way by bolts. The two parts of hanger 10 are secured together by bolts 13 in elongated openings 12 to the part 9, and at the lower ends of the two halves by bolts 15 through flanges 14. The pipe coupling member, 16, shown is of the butt type with the well known guide arms 17, 18 and 19 for the usual purpose. 20 represents a coupling arm, as shown it is disposed axially of the spring element composed of an extension member 21 and a compression member 22. The end plate or disk 23 on the rear end of the coupling arm is secured by bolts 24, and the rear end of the extension member is secured to the disk 23 by means of yoke and nuts 25. The forward end of the extension member is secured in like manner on each side of the hanger or ring 10 as shown at 26 of Figs. 1, 2, 3 and 6. On the front side of the hanger and behind the compression member 22 is an abutment collar 27. On the forward end of the coupling arm 20 is a pipe coupling member 16, which is provided with a rotatable valve 28 with crank 29 and valve rod 30. This rod and locking rod 32 at their rear ends are suitably connected to collar at 31 and 33 to permit of vertical and lateral movement. 34 denotes an aperture through the pipe coupling to receive the locking bar carried by an opposing pipe coupling member, and 35 indicates a like aperture in which rests the slideable locking bar 32. The usual gasket is shown by 36 and the air hose by 37.

The spring element preferably is composed of an extension spring and a compression spring tandem. The extension member has one end free to permit radial deflection thereof. It will be noticed I have shown a butt type of pipe coupling member but my invention is adapted to the side-port type as well.

As shown in Fig. 6, and by dotted lines in Figs. 1 and 2 the front and rear of the opening through the hanger or ring portion 10 of the depending bracket is concave and the inner surface of the opening is convex to permit deflection of the coupling arm 20. The pipe coupling member may be increased in dimensions to provide additional ports and the rotatable valve made to regulate the flow of fluid in each pipe. The description of my improvement as attached to one M. C. B. coupler is a description of both as each is a duplicate of the other. It will be apparent the coupling arm has movement through the

ring portion 10 of the depending bracket, and also may be deflected in any direction from its horizontal axis. The abutment collar 27 is in slidable contact with the front outer face of the ring 10. The upper front surface of the ring 10 is cut away sufficiently to permit vertical movement of the collar 27. The rear portion of the extension member 21 will tend not to be deflected excepting when it is extended in coupling or while in coupled position. The extension member and the compression member will maintain the coupling arm in horizontal position, and will keep the faces of the pipe coupling members in constant contact while the car couplers are in coupled position. The slidable locking bar is intended to prevent movement of the pipe coupling members relative to one another while in coupled engagement and are automatically withdrawn when the cars separate or become uncoupled. It is thought a mechanic will readily assemble the respective parts and therefore no further description is given. In practice it is desirable to be able to adjust the hanger 10 relatively to the car coupler, and this is possible by elongated openings 12 and bolts 13.

In operation when two cars approach each other for coupling of the cars the guide arms 17, 18 and 19 will first engage and the faces of the pipe coupling members will contact in a position so the gaskets will register and the apertures 34, 35 will register, then the extension member will be extended and the compression member will be compressed as each coupling arm is caused to move rearwardly through the hanger or ring portion 10 of the depending bracket and simultaneously the locking bar and the valve mechanism will be operated, the former will be extended into the open aperture of the opposing pipe coupling member and the latter will be rotated to open position, and vice versa when the cars are being uncoupled.

Having thus fully described my invention, what I claim as new, and desire to secure by Letters-Patent, is

1. In a train pipe coupling a pipe coupling member having an aperture therethrough and a locking bar slidably seated therein and adapted to be pushed through into an aperture in an opposing pipe coupling member by the recession of said members in the act of coupling.
2. The combination of a pipe coupling member having an aperture and a locking bar slidable therein, with a rotatable valve in the pipe coupling member.
3. The combination with a pipe coupling member having an aperture and a locking bar slidable therein and adapted to be pushed into an aperture in an opposing pipe coupling member by the recession of said members in the act of coupling, of a rotatable valve and means for rotating the valve.

4. In a train pipe coupling, a depending bracket, an extension member, a coupling arm, a pipe coupling member, and a locking bar capable of being extended through the pipe coupling member.

5. A train pipe coupling comprising a depending bracket, an extension member, a compression member, a coupling arm, a pipe coupling member, a locking bar, and a rotatable valve in said pipe coupling member.

6. A train pipe coupling comprising a depending bracket, an extension member, a compression member, a coupling arm, a pipe coupling member, a locking bar, a rotatable valve and means for rotating said valve.

7. A train pipe coupling comprising a depending bracket with an opening therethrough having concave front and rear surfaces and a convex inner surface, an extension member, a coupling arm, a pipe coupling member, and a locking bar capable of being extended through said pipe coupling member into an opposing member.

8. A train pipe coupling comprising a depending bracket with an opening therethrough having concave front and rear surfaces and a convex inner surface, an extension member, a compression member, a coupling arm, a pipe coupling member, and a locking bar capable of being extended through said pipe coupling member into an opposite member.

9. The combination with a car coupler having a depending bracket, of an extension member, a coupling arm, a compression member, a pipe coupling member, and a locking bar.

10. The combination with a car coupler having a depending bracket, of an extension member, a compression member, a coupling arm, a pipe coupling member, a locking bar and a rotatable valve in said pipe coupling member.

11. The combination with a car coupler having a depending bracket, of an extension member, a compression member, a coupling arm, a pipe coupling member, a locking bar, a rotatable valve and means for rotating said valve.

12. The combination with a car coupler having a depending bracket, of an extension member, a compression member, a coupling arm, a pipe coupling member, and means for locking said pipe coupling member to an opposing member.

13. The combination with a car coupler having a depending bracket, of a compression member, a coupling arm, a pipe coupling member, and a locking bar capable of being extended through the pipe coupling member.

14. The combination with a car coupler having a depending bracket, of a compression member, a coupling arm, a pipe coupling member, and a slidable locking bar.

15. The combination with a car coupler

- having a depending bracket, a compression member, a coupling arm, a pipe coupling member, a rotatable valve in said pipe coupling member, and a locking bar.
- 5 16. The combination with a car coupler having a depending bracket, of an extension member, a coupling arm, a compression member, an abutment collar and a pipe coupling member.
- 10 17. The combination with a car coupler having a depending bracket, of an extension member, a coupling arm, an abutment collar, and a pipe coupling member.
- 15 18. The combination with a car coupler having a depending bracket, of a compression member, a coupling arm, an abutment collar, and a pipe coupling member.
19. The combination with a car coupler having a depending bracket, of an extension member, a coupling arm, an abutment collar, 20 a compression member, a pipe coupling member and a locking bar.
20. The combination with a car coupler having a longitudinally adjustable depending bracket, of an extension member, a coupling arm, a locking bar, a compression member 25 and a pipe coupling member.

In testimony whereof I affix my signature in presence of two witnesses.
